(57) **CLAIM**

The ornamental design for a pool vacuum head, as shown and described.

DESCRIPTION

FIG. 1 is a front, right, perspective view of a pool vacuum head in accordance with the present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, left, perspective view thereof;

FIG. 9 is a bottom, right, perspective view thereof; and,

FIG. 10 is a bottom, left, perspective view thereof.

The broken lines shown in the drawings illustrate portions of the pool vacuum head that form no part of the claimed design.

1 Claim, 9 Drawing Sheets
